[57] CLAIM

The ornamental design for a hands free controller for video games, as shown and described.

DESCRIPTION

FIG. 1 is a perspective view of a hands free controller for video games showing my new design;

FIG. 2 is a front elevation thereof;

FIG. 3 is a right side elevation thereof;

FIG. 4 is a left side elevation thereof;

FIG. 5 is a top plan thereof;

FIG. 6 is a rear elevation thereof; and,

FIG. 7 is a bottom plan view thereof.

The broken lines showing a harness strap in FIG. 1 is for illustrative purpose and forms no part of the claim. The flexible conduit shown in broken lines is for ease of illustration.

FIG. 5

FIG. 7

FIG. 1

*FIG. 3**FIG. 2*FIG. 6

FIG. 4
